[57] CLAIM

The ornamental design for an electric plant sprayer, as shown and described.

DESCRIPTION

FIG. 1 is a front perspective view of an electric plant sprayer showing my new design with the nozzle detached from its body;

FIG. 2 is a top plan view thereof with the nozzle attached to the body;

FIG. 3 is a bottom plan view thereof;

FIG. 4 is a front elevational view thereof;

FIG. 5 is a left side elevational view thereof; and

FIG. 6 is a rear elevational view thereof.

FIG - 4

FIG - 5

FIG - 6
